MOP CLEANING ATTACHMENT

Edward J. Franta, Cicero, Ill.

Application June 26, 1947, Serial No. 757,112

2 Claims. (Cl. 15—246)

1

The present invention relates to a mop cleaning attachment particularly adapted to be attached to the mop stick or handle of any mop to facilitate the removal of dust and dirt from the mop.

It is an object of the present invention to provide an attachment for the mopstick or handle whereby the mop may be readily and quickly cleaned of dust and dirt.

It is a further object of the present invention to provide a mop cleaning attachment whereby centrifugal force may be employed to clean the mop.

It is a still further object to provide a mop cleaning attachment which is relatively simple in construction so as to be economical to manufacture, and which may be readily attached to and removed from a mopstick without the use of tools.

Other and further objects of the present invention subsequently will become apparent by reference to the following description taken in conjunction with the accompanying drawings wherein:

Figure 1 is a perspective view illustrating the application of the invention to a mop;

Figure 2 is a longitudinal cross-section view of one embodiment of the present invention;

Figure 3 is a cross-sectional view of the embodiment shown in Figure 2 as seen in the direction of the arrows along the line 3—3;

Figure 4 illustrates another variation of the invention as seen in longitudinal cross-section;

Figure 5 is a cross-sectional view of the embodiment shown in Figure 4 as seen in the direction of the arrows along the line 5—5; and

Figure 6 illustrates by means of a longitudinal cross-section still another variation in the embodiment of the present invention.

Referring more particularly to Figure 1 there has been shown the application of the present invention to a dry mop commonly called a dust mop, or when the mop material has been impregnated with a suitable fluid, the mop is called a dustless mop. Such mop has a handle or mop stick 11 which carries a mop head 12 which supports the mop or mop material 13. The present invention consists of a mop cleaning attachment 14 positioned at an intermediate point on the mop stick or handle 11 so that it may be grasped by one hand. The other hand of the individual grasps the upper end of mop stick or handle 11 and alternately rotates it in the direction of the arrows. This produces a rotary motion of the mop 13 as indicated by the arrows so that centrifugal force throws outwardly any dust, lint or threads that have been picked up by the mop.

2

In one embodiment as illustrated in Figures 2 and 3 the present invention or device 14 is formed of two tubular members 15 and 16 which may be held together by suitable securing means such as the cooperating threaded portion 17. The outer extremities of the members 15 and 16 of the device 14 have reinforced end bearing members 18 and 19 respectively which fit closely to the outer surface of the handle 11.

10 The members 15 and 16 are so arranged that adjacent their joined or threaded portion 17 there is formed a recess 21. Mounted within the recess 21 is a collar 22 which carries a plurality of inwardly projecting friction tabs 23 arranged to engage the outer surface of the handle or stick 11. From Figure 2 it is quite apparent that the outer extremity of each of the tabs 23 is curved so that it does not engage the surface of the handle 11 with such force as to mar or scratch the surface when the device 14 is being placed in position.

At least four tabs 23 are provided as is apparent from Figure 3, although it will be understood that a greater number could be employed.

15 Half of the tabs 23 extend in one direction, and the remainder extend in the opposite direction as is illustrated by Figure 2. The friction tabs or supporting means 23 retain in position the ring 22 which in turn determines the position of the device 14 on the handle 11. Sufficient clearance is provided in the groove 21 with respect to the ring 22 that the members 15 and 16 may be gripped by the hand and held stationary while a rotational force is applied to the handle or stick 11 as illustrated in Figure 1. Such rotational force does not place an undue strain upon the handle 11 as is the case where an oscillating motion is imparted to the handle 11 in the customary manner which often is accompanied by further shock when the mop material 13 is tapped against a solid or rigid object.

Another variation of the construction of the device 14 is illustrated in Figures 4 and 5. In these figures the manner in which the two members 15a and 16a are joined together differs from the threaded engagement provided in Figures 2 and 3. In Figure 4 the member 16a is provided with a recess 25 located adjacent a rib or ring 26 which may be semi-circular in cross-section. The member 15a is provided with an annular recess 27, which recess corresponds to the recess 21 of the preceding embodiment. Adjacent the recess 27 the member 15a is provided with an annular groove substantially complementary to the ring 26 of the member 16a. This stepped portion or groove 28 is adjacent to a

lip or annular portion 29 which may be bent inwardly as shown in Figure 4. Such an arrangement is particularly possible where the two members 15a and 16a are formed of plastic material, since the edge portion 29 may be formed inwardly in any suitable manner, although other interlocking constructions may be used.

Fitted within the recess 27 of the member 15a is a ring 31 having parallel flanges 32 adapted to engage the side walls of the recess 27 thereby to limit the axial movement of the member 14a. The ring 31 is provided with a plurality of friction engaging tabs 33 which alternately are arranged to extend in opposite directions. Here again the outer edges of the tabs 33 are curved so that the edge portions thereof will not in any way mar the outer surface of the stick or handle 11. The ring 31 therefore serves to frictionally determine the location of the rotatable member 14a on the handle 11.

Still another variation in the construction is illustrated in Figure 6 which shows that the member 15b is provided with a recess 34 for receiving toroidal spring 35. The spring 35 frictionally grips the stick or handle 11 and thereby positions the member 14b. The manner of constructing the two members 15b and 16b may be similar to that illustrated in Figures 4 and 5.

From the foregoing it will be noted that the attachment for the handle of the mop is readily placed in position where it remains until the device is to be removed for application to another mop. The bearing surfaces 19 and 18 permit ready rotation with adequate support so as to facilitate centrifugal cleaning of the mop material. In all embodiments a centrally located friction attachment device is employed for positioning the member 14. The construction is simple and economical to manufacture, and does not require any special tools for its installation. The device is a substantial guarantee against breakage of the handle 11 during the mop cleaning operation.

While for the purpose of illustrating the invention, there is shown in the drawings a par-

ticular embodiment with variations thereof, it is to be understood that the invention is not to be limited thereby since such further variations in the construction are contemplated as may be commensurate with the spirit and scope of the invention set forth in the appended claims.

What I desire to protect by United States Letters Patent is claimed:

1. A mop cleaning attachment comprising a sleeve having bearing surfaces at each end adapted to receive the handle of a mop, said sleeve having at its center an internal annular groove, a stamped ring member mounted in said groove, said member having a plurality of oppositely arranged friction fingers for gripping said handle to position said attachment thereon, said sleeve being arranged to revolve freely about said ring member.
2. A mop cleaning attachment comprising a sleeve having bearing surfaces arranged at opposite ends to receive the handle of a mop, said sleeve having an internal annular groove, said sleeve being formed in at least two portions connected together adjacent said annular groove, and a stamped metal ring mounted within said groove, said ring having a plurality of oppositely arranged friction tabs for resiliently gripping said handle to position said attachment thereon, said sleeve being arranged to revolve freely about said ring.

EDWARD J. FRANTA.
